UNITED STATES PATENT OFFICE.

WILLIAM LESTER LELAND, OF SAN FRANCISCO, CALIFORNIA.

HYDRAULIC ELEVATOR.

No. 884,818.

Specification of Letters Patent.

Patented Oct. 30, 1906.

Application filed March 2 1906. Serial No. 303,861.

To all whom it may concern:

Be it known that I, WILLIAM LESTER LELAND, a citizen of the United States, and a resident of San Francisco, in the county of San Francisco and State of California, have made certain new and useful Improvements in Hydraulic Elevators, of which the following is a specification.

My invention is an improvement in hydraulic elevators of the type used in placer-mining; and it consists in certain novel constructions and combinations of parts herein-after described and claimed.

Referring to the drawings forming a part hereof, Figure 1 is a longitudinal section of a part of my improved elevator in position in the pit. Fig. 2 is a section on the line 2 2 of Fig. 1 looking in the direction of the arrow. Fig. 3 is a detail perspective view, partly in section, of the ring having the annular chamber; and Fig. 4 is a front view of the jacket.

In the present embodiment of my invention I provide an elbow-shaped casting A, of steel or other suitable material, having a longitudinal opening a^0 therethrough. The ends of the casting around the opening are internally screw-threaded, as at a^1 , and the arch of the casting is provided with a pivot-pin a^2 , adapted to engage a bearing b in a plate B, secured to a beam b' , arranged at a suitable angle within the pit.

One end of the casting is provided with an internal shoulder a^3 below the screw-threaded portion a^1 , and the inner face of the said shoulder a^3 is screw-threaded, as at a^4 , a second shoulder a^5 being arranged below the screw-threaded portion a^4 . Arranged longitudinally upon the lower face of the interior of the casting is the usual longitudinal vane a^6 , adapted to prevent swirling of the water, and the casting is provided with outward enlargements a^7 adjacent to the screw-threaded portion. A nozzle C, having its lower end screw-threaded, is engaged with the screw-threaded portion a^4 , the opening c' through the nozzle being reduced at the upper end thereof and the said nozzle at its upper end being externally screw-threaded, as at c^1 , and having a shoulder c^2 arranged below the screw-threaded portion for a purpose to be herein-after described. A cylindrical jacket D, having a circular opening d in the side thereof and externally screw-threaded at each end, as at d^1 , engages one of the screw-threaded portions a of the casting. An in-

ternal lining d^2 , having a circular opening d^3 registering with the opening of the jacket, is arranged therewithin, and the said jacket is concentric with the nozzle. The upper end of the jacket D is engaged by a reducing-ring 60 E, the said ring having a flange e internally screw-threaded, as at e' , for engaging the screw-threaded portion of the jacket, and the inner surface of the ring is screw-threaded, as at e^2 , for engagement by the screw-threaded end g of a discharge-casing G, the upper end of the said casing extending to a suitable point whereby to deliver the material passed outward through the elevator. A throat-liner H, of manganese steel or other suitable material, is arranged within the discharge-casing G, the lower end of the said liner projecting somewhat below the ring E. The liner H is reduced centrally, as at h' , and slopes outwardly therefrom at each end and 70 is maintained in its proper position by a set-screw h^2 , threaded through the casing G and engaging an opening h^3 in the side of the ring or collar. A wear-plate comprising a cylindrical lining K is arranged above the throat-liner H, the said lining being arranged within the casing G and resting upon the upper edge of said throat. The opposite end of the casting A is engaged by one end of an externally-screw-threaded sleeve m^1 , the opposite end of 80 the sleeve being engaged by an elbow M, having both of its ends internally screw-threaded, and to the outer end of the elbow is connected the water-supply pipe N.

It will be understood that the water from 90 the flume passes through a supply-pipe N, through the casting A and the nozzle C, past the circular opening in the jacket D, and out at the discharge-pipe G, carrying with it the water, sand, and gravel entering through the 95 circular opening in the casing, the device acting in a similar manner to that of the ejector-pump.

In practice it has been found that when the water in the pit is lowered to a point but 100 slightly above the opening in the casing the ejector refuses to work, becoming water-logged, and it is necessary to introduce air or foreign substances into the supply-stream or to introduce air through the circular opening 105 in the jacket. This is a very difficult operation to perform, since it must be done speedily, as the pit soon fills with water and valuable time is lost in searching for the opening in the jacket whereby to introduce air. To 110

overcome this objection, I have devised the mechanism shown in Figs. 1 and 3, the said mechanism comprising a cylindrical ring O, having an annular chamber o, the said ring 5 being internally screw-threaded at one end, as at o², and arranged around the upper end of the nozzle, the lower edge of the ring resting upon the shoulder c², before described. A plurality of openings o' connect the annular 10 chamber with the interior of the ring, the said perforations being inclined downwardly from the chamber, whereby to prevent the entrance of sand and gravel entering through the jacket-opening. An air-pipe o' is tapped 15 into the ring for supplying air to the annular chamber, the said pipe extending upwardly alongside of the discharge-pipe to a point above the level of the water in the pit.

In the operation of my improved elevator 20 the stream of water passing upwardly through the nozzle creates a suction in the annular chamber, drawing air therethrough and carrying it upward with it in its travel. It will be noticed from an inspection of Fig. 1 that 25 the opening of the ring O is of greater diameter than the opening through the nozzle, the force of the water thus tending, so to speak, to form around itself a coating of air drawn in from the annular chamber. In placing 30 my improved hydraulic elevator in the pit the casting may be placed in any suitable position for receiving the supply-pipe, and the elbow may be turned with reference to the casting whereby to bring it into better 35 position for connection with the said supply-pipe. Should the opening in the jacket not be properly placed with respect to the material to be excavated and removed, it may be rotated with respect to the casting whereby 40 to bring the opening into proper position.

The casting and the elbow may be manipulated in such manner as to entirely free the supply-pipe from the flume from curves.

Having thus described my invention, what 45 I claim as new, and desire to secure by Letters Patent, is—

1. A hydraulic elevator for placer-mining comprising an elbow-shaped casting having a longitudinal opening and a pivot-pin 50 adapted for engagement with a fixed bearing, and being provided in the longitudinal opening with a longitudinal vane, an elbow rotatably engaging one of the ends of the casting, the elbow being adapted for connection with a water-supply pipe, a cylindrical jacket rotatably engaging the opposite end of the casting, said jacket being provided 55 with a circular opening in the side thereof, a removable lining for the jacket having a circular opening registering with the opening in the jacket, a reducing-ring engaging the free end of the jacket and lining, a discharge-pipe connected with the ring, a throat-liner 60 removably supported in the discharge-pipe 65 above the jacket and a lining resting upon

the liner, a nozzle engaging the end of the casting within the jacket and concentric therewith, and means for supplying air to the stream of water passing from the nozzle, comprising a ring having an annular chamber, the inner wall of the ring being provided with perforations, and an air-pipe arranged alongside the discharge-pipe and communicating with the annular chamber. 70

2. In apparatus of the class described, the combination of an elbow-shaped casting having a longitudinal opening, and provided with a pivot-pin for engaging a fixed bearing, an elbow-pipe rotatably connected with one end of the casting, a supply-pipe connected 80 with the elbow-pipe, a jacket rotatably connected with the opposite end of the casting, said jacket having a circular opening in its side, a nozzle connected with the casting inside the jacket and concentric therewith, a discharge-pipe connected with the jacket, and means for supplying air to the water passing through the nozzle, comprising a ring having an annular chamber arranged above 85 the nozzle and concentric therewith, the internal diameter of the ring being of greater diameter than the internal opening of the nozzle, and said annular chamber having openings communicating with the internal opening of the ring, and an air-pipe communicating with the annular chamber. 90

3. In apparatus of the class described, the combination of an elbow-shaped casting having a longitudinal opening therethrough, and a pivot-pin adapted to engage a fixed bearing, a supply-pipe communicating with one end of the casting, a nozzle connected to the opposite end of the casting, a cylindrical jacket having an opening in the side thereof rotatably connected with the casting and 100 inclosing the nozzle, a discharge-pipe connected to the jacket, and means for supplying air to the stream of water passing from the nozzle, comprising a ring provided with an annular chamber having openings communicating with the inner face of the ring, 105 said ring being arranged above the opening of the nozzle and concentric therewith, and an air-pipe communicating with the annular chamber. 110

4. In apparatus of the class described, the combination with the elbow-shaped casting having a longitudinal opening therethrough and provided with a pivot-pin for engaging a fixed bearing, of a supply-pipe rotatably connected with one end of the casting, a nozzle connected with the opposite end of the casting, a jacket having an opening in its side encircling the nozzle and rotatable on the casting, a discharge-pipe connected with 115 the jacket, and means for supplying air to the water passing through the nozzle, comprising a ring having an annular chamber, encircling the nozzle and concentric therewith, said chamber having openings com- 120

minating with the inner face of the ring and means for supplying air to the annular chamber.

5. In apparatus of the class described, the combination with the elbow-shaped casting having a longitudinal opening, and a pivot-pin for engaging a fixed bearing, of a supply-pipe connected to one end of the casting, a nozzle connected to the opposite end of the 10 casting, a rotatable jacket having a side opening and concentric with the nozzle, a discharge-pipe leading from the jacket, a ring having an annular chamber communicating with the inner face of the ring, encircling the nozzle and concentric therewith, the diameter of the opening of the ring being greater than that of the nozzle, and means for supplying air to the annular chamber.

6. In apparatus of the class described, the combination with the hollow elbow-shaped casting having a pivot-pin for engaging a fixed bearing, of a supply-pipe connected with one end of the casting, a nozzle connected with the opposite end, a rotatable jacket having a side opening, encircling the nozzle and concentric therewith, a discharge-pipe leading from the jacket, a ring concentric with the nozzle, said ring having an annular chamber provided with openings traversing the inner wall thereof, and means for supplying air to the annular chamber.

7. In apparatus of the class described, the combination with the hollow casting, having a pivot-pin for engaging a fixed bearing, a supply-pipe rotatably connected with one end of the casting, a nozzle connected with the opposite end, a jacket having a side opening, encircling the nozzle and rotatably connected with the casting, a discharge-pipe 40 leading from the jacket, and means for supplying air to the water passing through the nozzle, comprising a hollow ring provided with perforations and arranged concentric

with the nozzle, and means for supplying air to the hollow ring.

8. In apparatus of the class described, the combination of a hollow elbow-shaped casting having a pivot-pin for engaging a fixed bearing, a rotatable elbow-pipe connected with one end of the casting, a water-supply pipe connected to the elbow, a reducing-nozzle connected with the opposite end of the casting, a cylindrical jacket having a side opening, encircling the nozzle and connected therewith, and a discharge-pipe leading from the jacket and in alinement with the opening of the nozzle, said jacket being rotatably connected with the casting.

9. In apparatus of the class described, the combination of a hollow elbow-shaped casting having a pivot-pin for engaging a fixed bearing, a water-supply pipe rotatably connected to one end of the casting, a reducing-nozzle connected with the opposite end of the casting, a jacket having a side opening, encircling the nozzle and rotatably connected with the casting, and a discharge-pipe leading from the jacket in alinement with the nozzle.

10. In apparatus of the class described, the combination with the hollow elbow-shaped casting, of means for rotatably mounting the casting, a water-supply pipe rotatably connected to one end of the casting, a nozzle connected with the opposite end thereof, a jacket having a side opening encircling the nozzle and rotatably connected to the casting, and a discharge-pipe leading from the jacket in alinement with the nozzle, said discharge-pipe being rotatably connected to said jacket.
